FOREIGN PATENT DOCUMENTS

WO WO/99/42020 8/1999

Primary Examiner — Holly Baynham

(74) Attorney, Agent, or Firm — Greenberg Traurig, P.A.

CLAIM

what is claimed is the ornamental design for an adjustable display bracket, as shown and described.

DESCRIPTION

FIG. 1 is a top front perspective view of the ornamental design;

FIG. 2 is a rear side perspective view thereof;

FIG. 3 is a bottom view thereof;

FIG. 4 is a front elevational view thereof;

FIG. 5 is a top view thereof;

FIG. 6 is a rear side elevational view thereof;

FIG. 7 is a left side view thereof;

FIG. 8 is a right side view thereof;

FIG. 9 is a front perspective view with the two segments separated; and,

FIG. 10 is a rear perspective view with the two segments separated.

The broken lines shown in FIG. 1 are for the purpose of illustrating environment and do not form part of the claimed design.
